ROTARY INTERMITTENT FEED MECHANISM

George B. Scheffey, Reading, Pa., assignor to
J. H. Sternbergh, Reading, Pa.

Application November 27, 1944, Serial No. 565,275

11 Claims. (Cl. 271—2.4)

1

This invention relates to feed mechanism and more particularly to an intermittent feed mechanism adapted to be used with a high speed punch or die press where a strip of metal is fed to the press to be formed thereby into the desired article.

In presses of this kind it is usual to form first pilot holes in the strip whereby it is thereafter fed a uniform distance as each successive die or punching operation takes place. The present invention is directed primarily to mechanism for feeding a strip of material to the press in uniform amounts at each cycle of the feed mechanism and it is a main object of this invention to provide feed mechanism which will be extremely accurate and reliable and at the same time one which may be easily and quickly adjusted for feeding the material any desired predetermined amount without rebound.

A further object is to provide a feed mechanism in which the original setup of adjustment may be quickly made and subsequently permit minor adjustments while the machine is in operation as may be necessary.

It sometimes happens that after a machine has been running for an appreciable length of time, it is said to "warm up" and subsequent adjustments of a very minor character may be necessary to permit the pilot pin to enter the pilot holes in the strip more exactly.

Further, as the metal strip to be operated upon frequently comes in large coils, it is necessary to make adjustments as the size of the coil diminishes for there is less momentum to the strip which gradually causes a slight variation in the amount of feed. It is, therefore, a further object to provide a brake adapted to coact with the feed mechanism to insure a more exact periodic feed of uniform amounts.

A further object is to provide a mechanism of the above character having relatively few parts which may be inexpensively manufactured and assembled.

A further object is to provide a mechanism forming a substantially independent unit which may be attached to or secured to any desired form of punch or die press and be removed therefrom as desired.

A further object is to provide an efficient mechanism of the above character in which all the operating parts are connected to a single main source of power on the press itself.

Other objects will be in part obvious from the annexed drawings and in part hereinafter indicated in connection therewith by the following analysis of this invention.

2

This invention accordingly consists in the features of construction, combination of parts, and in the unique relation of the members and in the relative proportioning and disposition thereof, all as more completely outlined herein.

To enable others skilled in the art fully to comprehend the underlying features of this invention, that they may embody the same by the modifications in structure and relation contemplated by the invention, drawings depicting the preferred embodiments of the invention form a part of this disclosure, and in such drawings like characters of reference denote corresponding parts throughout the several views in which—

15 Fig. 1 is a side elevational view of the complete unit adapted to be secured to the die press.

Figs. 2 and 2a are the upper and lower portions of the mechanism shown in Fig. 1, taken at right angles thereto.

20 Fig. 3 is a detailed view of the feed roller release mechanism partly in section.

Fig. 4 is a detailed view of the brake mechanism. Figs. 5 and 6 are detail views of a release attachment.

25 Fig. 7 is an enlarged diagrammatic view of a portion of the structure of Fig. 5 showing the pivotal connection between the link for raising and lowering a feed roll and the link operating arm.

30 Referring now to the drawings in detail, Fig. 2 will first be considered, wherein a main drive shaft 10, mounted in suitable bearings 11, is secured on brackets 12 bolted to the frame of the press not shown in detail. This shaft 10 is driven from any convenient source of power preferably that used in driving the press by means of a sprocket 14 mounted at one end of the shaft 10. The opposite end of this shaft is provided with a crank disc 15 upon which is mounted a slide 16 for a block 17 (Fig. 1) which may be moved relatively with respect to the center of the disc 15 thereby to vary the stroke of the pin 18 as the disc revolves.

45 Mounted upon the pin 18 is a reciprocating connecting link or crank arm 21 preferably formed in two parts as shown which parts are connected by means of an adjusting turn buckle 22 held in adjusted position by lock nuts 23. The lower end of this two-part connecting rod 21 is provided with a pin 24 to which is attached a link 25 terminating in a pin 26 at one end of link 27 mounted upon a shaft 28 carrying in a bearing the lower of two feed rollers 30 and 31.

50 Also on the pin 24 is a second link 32 the opposite end of which is pivotally mounted on a pin

55

33 at one end of an adjusting screw 34 slidably movable in a block 35 constituting a fixed part of the frame. A micrometer screw and nut 36 is also mounted on this adjusting screw 34 and operating between fixed abutments 37 and 38 on the frame whereby as this nut 36 is turned the adjusting screw is moved to the right or left according to the direction in which the nut 36 is turned. Thus if the screw 34 is moved towards the right such movement will cause a relative movement of the pin 24 to the right thereby changing the normal angle between the links 21 and 25 to vary the up and down throw of the arm 27 which, of course, will vary the amount of material fed between the feed rollers 30 and 31.

As previously stated this feed mechanism is of the intermittent type adapted to feed a predetermined amount of material indicated by the strip 40 at each cycle of operation. Therefore, the feed rolls 30 and 31 have a counter-clockwise movement during the upstroke of the connecting rod 21 at which time they engage the lower and upper surfaces of the strip 40, respectively, but on the downstroke of the link 21 it is necessary that these feed rollers be out of actual feeding contact with the strip. Accordingly, means must be provided for slightly separating the centers of the rollers during this downstroke to prevent a backward or rebound movement of the strip.

Reverting to Fig. 2 there is mounted on the main power shaft 10 a rotary cam 41 having a raised adjustable portion 42 coacting with a roller 43 which is normally urged into engagement with the cam by means of a spring 44 secured at one end to a fixed bracket 45 and its lower end to a pivotally mounted arm 46. This arm Fig. 3 is pivoted at 47 on a fixed bracket 48 secured to the frame of the press. The outer end of the arm has a pin 50 forming a pivot for the lower end of an adjustable tie rod 51 the upper end of which rod is pivoted at 52 to an arm 53 pivotally mounted on bracket 45, the end of which latter arm carries the cam roller 43 cooperating with the cam. Thus the frame of the press, arms 46 and 53, and adjustable turn buckle link 51 constitute a flexible parallelogram in which the roller 43 is always held yieldingly in contact with the cam and has a slight relative up and down movement to rock the shaft 47 a very slight degree.

Referring now to Fig. 1, it will be seen that as the shaft 47 is rocked the feed rollers will be slightly moved by reason of the intermediate mechanism which comprises a short arm 54 keyed to the shaft 47 and pivotally mounted or connected at 55 with a vertical link 56 bearing upon the top of a block 57 in which is journaled shaft 28a carrying the feed roller 31, and adjustable stop 58 will limit the upward movement of this block 57 which is normally forced upwardly by means of spring 60 on the under side of the block which spring reacts against a second block 61 which carries the lower feed roll 30. Thus when the downward pressure exerted upon the link 56 is released by the upward movement of the link 51 then the blocks 57 and 61 are slightly separated by the action of the spring 60 to the extent of a few thousandths of an inch which is sufficient to relieve the feeding action on the strip by the feed roller.

In order to control the rate of speed of the strip 40 and render the same uniform, there is provided a brake mechanism as shown at the right of Fig. 1, which includes a rectangular chamber 62 having, in this case, two transverse

shafts 63 of angular cross section to each of which is fixed and inclined plate or finger 64 shown in Fig. 4. These plates or tension fingers, as they are sometimes called, are adapted to bear downwardly upon the upper surface of the strip 40 with the desired pressure. The plates 64 are mounted upon rock shafts 63 and about one end of each there is an adjustable coil spring 65 one end of which 66 is fixed to a side wall of the box 62 while the opposite end 67 is fixed to an adjusting nut 68 which is adapted to be secured to the shaft 63 by means of a cotter or the like 70 which engages in a recess in the nut 68. Nut 68 is slideable along shaft 63 and when released from the cotter pin 70 by pressing it inward against the action of the spring 65 may be turned around the shaft 63. It will thus be seen that by pressing the nut toward the left in Fig. 4, turning the nut and allowing it to move backward to the right so that the cotter pin 70 reengages in the notch the tension of the spring and consequently the pressure of the plate 64 on the strip 40 may be set at a different value.

The parts just described with relation to Fig. 2a are shown in their assembled relation in Fig. 2a which also shows the mounting of the feed rolls 30 and 31. The shafts carrying the feed rollers are preferably mounted in two sets of bearings 71 and 72 and carry gears 73 whereby the two shafts upon which the feed rollers are mounted are geared together to rotate uniformly. By mounting the shafts in this manner any relative angular motion is positively prevented.

While the operation of the present machine is clear from the above description, the entire series of steps and operation may be briefly summed as follows:

In setting up the machine for operation the distance that the strip is to be moved at each cycle is definitely determined in accordance with the article to be made by the die press, which incidentally may be of that type shown and described in my prior United States Patent No. 2,318,107. The first adjusting means shown at the top of Fig. 1 is operated to determine the stroke of the connecting rod 21 which of course has a direct relationship to the intermittently operating feed rollers 30 and 31. The strip is then passed into the machine from the right and under the brake or tension fingers 64 until it contacts with the periphery of the adjacent feed rollers. These feed rollers are separated until the end of the strip coacts with a stop in fixed relation to the first punch and pilot pin. The machine is then started to operate synchronously with the die press and the strip moves forwardly to the left under the action of the feed rollers.

This takes place as previously explained only on the up stroke of the connecting rod. As soon as this rod reaches the top of its stroke, then the cam 42 shown in Fig. 3 is in position to permit the cam roller 43 to move upwardly under the action of the springs 44 and 60. This causes a rocking of the shaft 47 in a counter-clockwise direction thereby relieving the down pressure of the rod or link 56 on the top block 57 of the feed rollers, whereupon the springs 60 between the upper and lower feed roller blocks immediately come into action to force the blocks apart, thereby carrying the two shafts upon which the feed rollers are mounted relatively away from each other as clearly shown in Fig. 2a. Then on the downward movement of the connecting link 21 the rollers operate in a reverse direction with out moving the work strip at all. On comple-

tion of this downward movement of the connecting rod 21 the cam 42 has completed its half cycle to depress again the roller 43 and rock the shaft 47 in a clockwise direction thus to exert through the link 56 a downward pressure upon the block carrying the feed roll 31 and compress the springs 60 whereupon the feed rollers are in a position again to feed the work strip 40 towards the left as soon as the up stroke begins.

If the strip is feeding sluggishly the brake fingers 64 are adjusted as may be necessary to ease the braking action. These fingers, however, should always bear upon the strip with sufficient force to prevent any movement of the strip by reason of its momentum and prevent rebound.

If for any reason the pilot pin is not properly coacting with the pilot holes in the work strip, this may be easily and completely corrected while the machine is still operating by turning the micrometer nut 36 in the desired or necessary direction, thereby to change the extent of stroke or the effective length of the connecting link between the points 18 and 26.

It will be noted from the construction shown in Fig. 1, that a relatively larger adjusting movement of the pivot 33 will result in a relatively small change in the extent of oscillation of the feed roll. In other words this adjustment is a micrometer adjustment.

In Figs. 5 and 6 are shown details at right angles of a release mechanism for the feed rolls 30 and 31 for it sometimes happens that these stop from a previous operation in contacting or feeding position instead of separated. Obviously they must be separated in order to put in a new strip. Accordingly, the lever 54 in Fig. 1 mounted on shaft 47 is made triangular in form as indicated in Fig. 5 having a base the same as 54 and two included members 71 and 72 joined at the top and formed at the top with an opening or hole 73. An arm 74 is keyed to a shaft 55 rotatably mounted in the base portion of the arm 54' and shaft 55' is formed with an eccentric portion 75 which forms a pivotal bearing for the upper end of link 56. Arm 74 carries an operating handle 76 at its upper end and handle 76 carries a locking pin 77, which is adapted to engage in the opening 73 or in an opening 78 in the shaft 50 at the outer end of lever 54'. This handle and pin are of well known construction whereby when the handle is pulled out against the action of an internal spring (not shown) the pin 77 will be removed from the hole 73 whereby the arm 74 is free to be swung downwardly to normal position when the pin may engage a hole 78 in the shaft 50 to lock the parts in position.

It will thus be seen that in normal operation the lever 74 is in its horizontal position with the pin 77 engaging the recess or hole 78. If, however, the machine should stop with the feed rollers 30 and 31 in feeding engagement, a simple movement of the handle 76 to its vertical position as shown in Fig. 5 causes the eccentric bearing 75 to move to the position shown in Fig. 6 thereby to raise the link 55 which normally presses down on the top of the upper feed roll 31 against the action of the spring 60 to hold these positively in feeding relation until released by the up stroke of the link 51 supplemented by the action of the spring 44.

It is thus seen that the present invention is directed to a simple and practical feed mechanism for metallic strip passing to a die press

or the like, in which the strip is to be fed intermittently and in exact predetermined amount. The mechanism primarily permits an easy and quick setup in the initial stages as well as refinements of initial adjustments while the machine is still operating, not only to control and rectify the rate of feed, but the extent of feed thereby to insure reliability and efficiency of operation at all times.

10 While it will be apparent that the illustrated embodiments of this invention herein disclosed are well calculated adequately to fulfill the objects and advantages primarily stated, it is to be understood that the invention is susceptible to variation, modifications and changes within the spirit and scope of the following claims.

I claim:

1. An intermittent rotary feed mechanism of the character described, in combination, a crank 20 arm, a disc upon which it is pivotally connected at one end, a link at the other end of the crank arm, feed rolls actuated by said link cam actuated means positively holding the said feed rolls in engagement with the strip to be fed 25 during substantially half the cycle of operation and spring releasing means for holding the rolls out of engagement during the other half cycle while the punching is taking place, and means for adjusting the end of said crank arm with 30 respect to the center of the disc to which it is connected to vary the effective length of stroke of said link.

2. An intermittent feed mechanism of the character described, in combination, a crank 35 arm, a disc upon which it is pivotally supported, a roller feed device, means for positively holding said device in feeding engagement during substantially half of each cycle of operation, an oscillating link normally arranged at an angle 40 to said arm and connected to the feed device at one end and to the outer end of the crank arm at its other end, means for adjusting the end of said crank arm with respect to the center of the disc to which it is connected, means for 45 varying the length of the rod, and means for changing the angle between the arm and connecting link to vary the feed of material.

3. An intermittent feed mechanism of the character described, in combination, a reciprocating link member, a roller feed device, means for positively holding said device in feeding engagement during substantially one half each cycle of operation, a link normally in angular relation to said reciprocating link member and 55 connecting said member with one roller of said feed device, means for adjusting the amount of feed by varying the angle between the two links and thus changing the amount of reciprocation of the feed, a source of power and operating 60 connections between said source and said member

4. An intermittent feed mechanism of the character described, in combination, a reciprocating member, a roller feed device, means for 65 positively holding said device in feeding engagement during substantially one half of each cycle of operation, a link normally in angular relation to said reciprocating member and connecting said member with one roller of said feed 70 device, means for adjusting the amount of feed by varying the amount of reciprocation of the reciprocating member, other feed adjusting means comprising a device mounted on the frame of the machine for varying the angle between the reciprocating member and connecting

link, a source of power and operating connections between said source and reciprocating member.

5. An intermittent feed mechanism of the character described, in combination, a reciprocating member, a roller feed device including two cooperating rollers between which the work is fed, means for positively pressing said roller against the work during substantially one half of the cycle of operation whereby the work is fed and means separating said rollers during the other half of said cycle, a link normally at an angle to said reciprocating member and connecting the member and one roller of the feed device, means for adjusting the feed by varying the amount of reciprocation of the reciprocating member and means for adjusting the feed by varying the angle between said members and link, a source of power and operating connections between said source and members.

6. An intermittent feed mechanism of the character described, in combination, a crank arm, a disc upon which it is pivotally supported, a roller feed device, means for positively holding said device in feeding engagement during substantially half of each cycle of operation, an oscillating link normally arranged at an angle to said arm and connected to the feed device at one end and to the outer end of the crank arm at its other end, and means for changing the angle between the crank arm and the connecting link to the feed roller.

7. An intermittent feed mechanism of the character described, in combination, a source of power, a rotatable member driven thereby, a crank arm pivotally mounted on said member, means for adjusting said arm with respect to the center of said member, a feed mechanism comprising two rollers between which material is fed, means for positively pressing said rollers against the material for feeding the same during substantially one half of the cycle of operation, a link for driving one of the feed rollers and connected between said one roller and said crank arm, said link being normally arranged at angle to said arm and means for varying said angle to adjust the amount of material fed.

8. An intermittent feed mechanism of the character described, in combination, a source of power, a disc rotated thereby, a reciprocating link pivotally mounted on the disc, feed rollers, a feed roller operating link connected to a roller and to said first named link and normally arranged at an angle to said first named link, means for varying said angle to adjust the amount of material fed, a movable bearing for one of the rollers, means for pressing said rollers against the material to be fed for feeding the same and for releasing the pressure on the rollers, said last

named means including a cam operated by said source and connections between said cam and said bearing.

9. The intermittent feed mechanism as set forth in claim 8 wherein springs are provided for separating the rollers on release of said pressure.

10. An intermittent feed mechanism of the character described, in combination, a pair of feed rollers between which the material to be acted upon is passed, spring means for moving said rollers out of feeding engagement during substantially one half of the cycle of operation and means for positively pressing said feed rollers into feeding engagement with said material during the remaining half of the cycle, said latter means including a source of pressure and operating connections between said source and one of the rollers, said connections including a movable member, a pin rotatably mounted in said movable member and having an eccentric portion, a connecting link pivotally mounted on said eccentric portion and serving to transmit feeding pressure to said one roller and manually operated means for turning said pin in its mounting so as to relieve the pressure when desired should the machine stop with the feed rollers in feeding relation.

11. An intermittent feed mechanism of the character described, comprising in combination, a frame, a roller feed device mounted on said frame, means for operating said device to intermittently feed material, said means including a drive and two links pivotally connected respectively at one end to the device and to the drive and pivotally connected together at their opposite ends, and arranged at an angle to one another, a third link pivoted at one end to a point relatively fixed with respect to the frame and at the other end to the point of connection between said first named links and manual means for adjusting the position of said relatively fixed point to change the angular relation of said first named links and the amount of feed produced by said feed device.

GEORGE B. SCHEFFEY.
